UNITED STATES PATENT OFFICE.

IRVING W. COLBURN, OF FRANKLIN, PENNSYLVANIA, ASSIGNEE, BY MESNE ASSIGNMENTS, TO TOLEDO GLASS COMPANY, OF TOLEDO, OHIO, A CORPORATION OF OHIO.

MEANS FOR DRAWING SHEET-GLASS.

1,156,273.

Specification of Letters Patent.

Patented Oct. 12, 1915.

Application filed August 14, 1908. Serial No. 446,485.

To all whom it may concern:

Be it known that I, IRVING W. COLBURN, of Franklin, Pennsylvania, have invented a new and useful Improvement in Means for Drawing Sheet-Glass, which improvement is fully set forth in the following specification.

This invention relates to the art of drawing sheet glass by a continuous process, and 10 more particularly to that class of glass commonly known as figured or cathedral glass, the characteristic of which is a figured, stippled or rough surface.

The leading characteristics of the invention relate more especially to the means by which the surface of the glass is given the desired configuration, and also to a novel method of maintaining the width of the sheet.

20 Other specific matters of improvement will be hereinafter referred to and then particularly pointed out in the claims.

The inventive idea involved is capable of 25 a variety of mechanical expressions, one of which, for the purpose of illustrating the invention, is shown in the accompanying drawings, in which—

Figure 1 is a sectional perspective view 30 of the working end of the machine showing the working chamber for the molten glass, the combined figuring and width-maintaining device, and the front end of the reheating chamber where the glass is reheated before it is passed over the bending roll from 35 a vertical to a horizontal position to be passed through the annealing leer; Fig. 2 is a side elevation of the front end of the machine, showing the means for driving the combined figuring and width-maintaining 40 rolls, a portion of the driving device being broken away to expose other portions to view; and Figs. 3 and 4 are broken details.

Referring to the several sheets of the drawings, in which like numerals indicate 45 like parts, 1 is the molten glass in any suitable working chamber, and 2 is the cover portion thereof through which there is a transverse opening.

3 is the bending roll located in the front 50 or forward end of the reheating chamber 4, and 5 is the carrier table which receives the sheet 6 after it has been bent from the vertical to the horizontal position over the bending roll 3, the sheet being grasped between the endless carrier table and the bars

7 on the drive-chains 8 for advancing it from the reheating chamber 4 to the leer this same gripping device serving to pull the sheet over the bending roll, after the sheet has been "drawn," that is, after it has been 60 formed by tension applied either to portions of the drawn sheet or to a bait which, as said sheet or bait rises from the molten mass of glass 1 in the drawing chamber, draws up other molecules of the molten mass 65 into sheet form. It is this formation of the sheet by drawing it out of the molten mass that is technically known in the art as "drawing". The sheet having been drawn is advanced into a portion of the open atmosphere below the entrance to the reheating chamber 4, and by reason of its exposure to this open atmosphere, it rapidly cools and 70 hardens, and it is therefore necessary, in order that the sheet may be bent from its 75 vertical to its horizontal position, that it be reheated, and thereby softened or rendered more plastic, in order that the bending action over the bending roll 3 may take place without danger of breaking the glass. Care 80 must be taken, however, at this point not to reheat the glass to such a degree of temperature that it will be softened sufficiently for the bending roll 3 to have any modifying effect thereon. For the purpose of effecting 85 this reheating, burners 8', 8', are inserted through openings in the front wall 9 of the machine, preferably delivering a blast of flame against the muffle 10, as shown in Fig. 1. As here shown, there is interposed 90 between the carrier table 5 and the bending roll 3 an idler roll 11 whose upper surface is slightly above that of the bending roll 3 and of the carrier table 5. If preferred, however, the bending roll 3 may be placed 95 with its upper surface in a slightly higher plane than that of the carrier table 5 and the intermediate roll 11 omitted.

All the revolving parts thus far described by preference are mounted upon hollow 100 shafts for the purpose of circulating a cooling fluid therethrough to obviate the deleterious effect of the heat incident to the operation of the machine.

Located in close proximity to the surface 105 of the molten glass 1 in the working chamber are two rolls 12, 12, mounted parallel to and in close proximity to each other in yielding bearings, such for example, as that shown at 13 in Fig. 2, where the bearing 110

- boxes for the two rolls 12, 12, are shown as yieldingly held pressed toward each other by springs 14, 14, acted upon by set screws 15, 15, in a manner that will be well understood. The two rolls are spaced the desired distance apart by means of set screws 16, passing through a lug 17 on one bearing box and reacting against a lug 18 on the other bearing box.
- 10 Referring to Figs. 2 and 4, 19 is a shaft driven by suitable connecting gearing from the main power shaft of the machine, and connected by a universal joint 20 to the shaft 21, turning in bearings 22 mounted on and rigid with the bearing box 23 of one of the rolls 12. Shaft 21 has a miter gear 24 meshing with a corresponding miter gear 25 on the shaft of one of the rolls 12, there being a spur gear 26 rigid on the shaft of said roll and gearing with a like spur wheel 27 on the shaft of the other roll 12. The teeth of the spur gears 26 and 27 are somewhat prolonged, so that even though the two rolls 12, 12, are somewhat separated, the teeth of the said wheels 26, 27, will nevertheless mesh, and the two rolls be thereby simultaneously driven through the operation of the shaft, but in reverse directions, with their adjacent faces moving upward and outward. The faces of these rolls 12, 12, are figured, as shown in Figs. 3 and 4, with the reverse of the pattern or stipple that it is desired to impress upon the face of the rolled sheet. The rolls 12 and the shafts 35 therefor are hollow, and means are provided for circulating water therethrough. The water may be either taken in at one end of the shaft on one side of the machine and permitted to flow out at the other end, as indicated in Fig. 4, or any other preferred construction may be employed. By mounting these rolls 12, 12, in close proximity to the surface of the molten glass 1 in the working chamber they serve not only to figure the glass in the desired manner, but they also perform an important part of the drawing operation proper, that is, of lifting the molten glass in sheet form from the molten mass 1, and they also serve to 40 counteract the tendency which drawn sheets of glass have to rapidly narrow to a string or thread as the drawing operation proceeds.
- 50 Preferably, the rolls 12, 12 are driven at a speed about one per cent. less than the motion of the carrier table 5 and the grip bars 7, whereby a certain longitudinal stretching action is imparted to the sheet between the point in the heating chamber 55 where the sheet is grasped by the grip bars 7 and the rolls 12, 12, in the working chamber.
- 60 If desired, the rolls 12, 12, in addition to the roughened or figured surface, may be provided at each end thereof adjacent to the end of said roughened surface, with
- annular flanges 30, 30 (see Fig. 3). As the sheet of glass is drawn upward by the rolls, these flanges contact with each other as shown in Figs. 3 and 5 and thus serve to determine the minimum thickness of the 70 drawn sheet.
- 75 It will be understood that the surface of the molten mass 1 in the working chamber is supplied with heat from any suitable source to maintain it in proper working condition, and for the purpose of still further tempering the glass and securing the precise working condition desired, I may, and sometimes do suspend on each side of the figuring rolls 12, 12, hollow shields 33, 33, through 80 which any suitable cooling fluid, as water, is circulated, entrance to said shields for the water being through the pipes 34, 34, the water finding exit through corresponding pipes at the opposite end.
- 85 Operation: The molten glass 1 in the working chamber having been brought to proper working condition, the formation of the sheet is initiated in the usual way by inserting a suitable bait into the mass of 90 molten glass, which, when the glass adheres thereto, is slowly elevated between the rolls 12, 12, which yield in their bearings for this purpose, the sheet of glass being formed as the result of the molecules of glass in the 95 molten mass following the bait as it is thus slowly elevated, this method of forming a sheet, as above stated, being technically known in the art as "drawing" the sheet. The bait having passed from between the 100 rolls 12, 12, the latter contact with the sheet, the pressure thereof upon the sheet being regulated by the adjustment of the set screws 15, the rolls 12, 12, performing the drawing operation after the bait has passed 105 upward beyond the rolls. The continued elevation of the bait, however, lifts the drawn sheet through the space between the rolls and the opening 36 in the bottom of the reheating chamber 4 and upward into said 110 chamber and over the bending roll 3, the idler roll 11, and between the carrier table 5 and the grip bars 7. The particular arrangement facilitating this operation of the bait has been fully described in my prior 115 Patent No. 836,439, and as it forms no part of the present invention need not be here dwelt upon in detail. The sheet having been "drawn," is materially chilled or reduced in temperature as it passes through the open 120 atmosphere between the rolls 12, 12, and the mouth 36 of the reheating chamber 4, but as it enters said chamber it is subjected to the action of the heat from burners 8', 8', and is reheated or softened to just that degree 125 where it can be bent over the bending roll 3 without breaking, without, however, being made soft enough to cause the bending roll to mar or in any way disfigure the impressions made upon the face of the sheet 130.

by the rolls 12, 12. During the elevation of the sheet from the rolls 12 to the mouth 36 of the reheating chamber 4, the drawn sheet is not only subjected to the cooling influence of the external atmosphere, but will also be more or less cooled by reason of the cooling influence of the water-cooled shields 33, 33, though the cooling action of such shields is not essential to the successful operation of the machine. The narrowing tendency of the sheet occurs between the bite of the rolls 12, 12, upon the sheet and the surface of the molten mass 1, and by reason of the hold which the roughened surface 15 of said rolls has upon the drawn sheet, this narrowing tendency is entirely overcome, and without imparting any lateral stretching action to the sheet. When the sheet of glass is drawn in the machine as described, 20 there is no lateral stretching action of the sheet whatever, and in fact no stretching action lateral or longitudinal, except when it is preferred to drive the rolls 12, 12, slightly slower than the corresponding movement of the carrier table 5 and the grip bars 7. The 25 drawn sheet having been cooled between the shields 33, 33, and by reason of exposure to the external atmosphere, advanced into the reheating chamber 4, and reheated by the burners 8', 8', is then bent over the bending roll 3, and received upon the carrier table 5, where it is seized by the grip bars 7 reacting against said table, and advanced into and through any suitable leer, where the 35 glass is gradually cooled and thereby annealed.

It will be understood that the skilled mechanician would be capable of embodying the inventive idea set forth in the above described machine in a variety of forms; that variations may be made in the proportions, and in some cases in the relative arrangement of the parts, and also in some cases some of the parts may be omitted, without

departing from the spirit of my invention, 45 which invention is as broad as the claims hereinafter appended.

What is claimed is:-

1. In a machine for drawing figured sheet glass from a mass of molten glass, a pair of sheet-drawing and sheet-figuring rolls located at the sheet-forming point and in contact with the sheet from edge to edge, and means for driving said rolls. 50
2. In a machine for drawing figured sheet glass from a mass of molten glass, a pair of sheet-drawing width-maintaining sheet-figuring rolls located at the sheet-forming point and in contact with the sheet from edge to edge, and means for driving said rolls. 55
3. In a machine for drawing figured sheet glass from a mass of molten glass, a pair of figured drawing rolls extending across and contacting with the sheet from edge to edge 60 at the sheet-forming point, and means for driving said rolls, whereby the sheet is simultaneously drawn, figured, and width-maintained by the single pair of rolls. 65
4. In glass-drawing apparatus, the combination of a receptacle for containing a mass of molten glass, a pair of oppositely disposed parallel width-maintaining rolls extending transversely across said receptacle, yielding bearings for the shafts of said rolls, gearing connecting said rolls, and a drive shaft operatively connected to the shaft of one of said rolls, said drive shaft turning in a bearing movable in unison with 70 the bearing of one of said rolls. 75

In testimony whereof I have signed this specification in the presence of two subscribing witnesses.

IRVING W. COLBURN.
